UNITED STATES PATENT OFFICE.

CAROLINE C. WISE AND CALLY T. RYLAND, OF RICHMOND, VIRGINIA.

DESIGN FOR A CLOCK-CASE.

49,408.

Specification for Design.

Patented July 18, 1916.

Application filed April 24, 1916. Serial No. 93,335. Term of patent 7 years.

● *To all whom it may concern:*

Be it known that we, CAROLINE C. WISE and CALLY T. RYLAND, citizens of the United States, and residing at Richmond, in the county of Henrico and State of Virginia, have invented a new, original, and ornamental Design for a Clock-Case, of which the following is a specification, reference being had to the accompanying drawing, forming part thereof.

Figure 1 is a front elevation of a clock

case embodying our design, and Fig. 2 is a side elevation thereof.

We claim:

The ornamental design for a clock case, as shown.

CAROLINE C. WISE.
CALLY T. RYLAND.

Witnesses:

HOLT S. LLOYD,
JNO. L. INGRAM.
